UNITED STATES PATENT OFFICE.

EDMOND W. T. RICHMOND, OF ROMFORD, ENGLAND.

DESIGN FOR A GAS-STOVE.

SPECIFICATION forming part of Design No. 33,880, dated January 8, 1901.

Application filed December 11, 1900. serial No. 39,560. Term of patent 7 years.

To all whom it may concern:

Be it known that I, EDMOND WALTER TYRRELL RICHMOND, a subject of the Queen of Great Britain, residing in Summerecourt, Romford, in the county of Essex, England, have invented and produced a new and original Design for Gas-Stoves, of which the following is a specification.

The accompanying drawing shows a perspective view of a gas-stove embodying my design.

The leading features of my design are the body portion A, having the flat top *a*, on which there is a series of rosettes or star-shaped figures A', the panels B at opposite ends of the front, the front upper portion C, having a series of parallel openings *c*, a cen-

tral panel D, the openings E on opposite sides of the panel, and the drawers F at the bottom of the openings. The three vertical panels are ornamented, and there is a front rail or pipe H, arranged horizontally in front of the stove and supported in brackets projecting from the panels.

I claim—

The design for a gas-stove, substantially as herein shown and described.

In testimony whereof I have hereunto subscribed my name.

EDMOND W. T. RICHMOND.

Witnesses:

KATHARINE MACMAHON,
EDWARD C. DAVIDSON.
